UNITED STATES PATENT OFFICE.

ADAM CLARKE, OF CHICAGO, ILLINOIS.

ODORLESS AND HUMIDITY-SUPPLYING HEATING-STOVE.

1,258,652.

Specification of Letters Patent. Patented Mar. 12, 1918.

Application filed April 30, 1917. Serial No. 165,344.

To all whom it may concern:

Be it known that I, ADAM CLARKE, a citizen of the United States, and a resident of Chicago, in the county of Cook and State 5 of Illinois, have invented certain new and useful Improvements in Odorless and Humidity-Supplying Heating-Stoves, of which the following is a specification.

This invention relates to improvements in 10 heating stoves or apparatus, for dwelling houses or other structures, of the class in which gas is used as fuel and in which the air is heated by its passage through tubes exposed to the heat of the burner and 15 through a heating drum surrounding the same, and it consists in certain peculiarities of the construction, novel arrangement and operation of the various parts thereof, as will be hereinafter more fully set forth and 20 specifically claimed.

While the invention relates particularly to heating stoves or furnaces, in contradistinction to stoves and ranges used for cooking purposes, and is so shown in the drawings and will be so referred to hereinafter, yet it will be understood that it is applicable for use in connection with ranges and cooking-stoves, and that numerous modifications and variations may be made therein without 25 departing from the spirit of the invention.

The principal object of the invention is to provide a stove which shall be extremely simple and inexpensive in construction, strong, durable and efficient in operation, 30 with its parts so constructed, arranged and operating as to afford means for the economical consumption of fuel, so as to furnish from the fuel and stove a maximum amount of heat, without the usual sensible 35 dryness or lack of moisture, incident to the heat produced by gas-stoves of the type heretofore commonly in use, and without the emanation and distribution of the usual noxious, poisonous and disagreeable odors, 40 soot and dust, or in other words, to provide a stove, which by reason of the novel construction, arrangement and operation of its parts, will prevent deleterious odors, fumes or products of combustion from the fuel 45 escaping into the room and commingling with the air to be breathed, and will conserve the moisture in the air, or supply moisture thereto as it is heated.

Other objects and advantages of the in-

vention, will be disclosed in the subjoined 55 description and explanation.

In the accompanying drawings, which serve to illustrate an embodiment of the invention,

Figure 1, is a view in vertical section of 60 the heater taken on line 1—1 of Fig. 2, looking in the direction indicated by the arrows, and

Fig. 2, is a plan sectional view taken on line 2—2 of Fig. 1. 65

Like numerals of reference, refer to corresponding parts throughout the different views of the drawings.

The reference numeral 7 designates the hollow base of the stove, which may be 70 made of any suitable size, form and material, but by preference, of metal and rectangular or box-like in form, as shown. The base 7 is used for the purpose of holding water and for the support of other parts 75 of the stove and has hinged thereto at one of its ends a lid or cover 8 which may be provided at its end opposite the hinges 9 with a hasp 10 to engage a suitable catch 11 on the upper portion of the case or receptacle 7, which hasp and catch are used for holding the cover 8 in its closed position. 80

As shown in Fig. 1 of the drawings the cover 8 is provided with an opening 12 and has at one end of said opening a downwardly deflected baffle-plate 13 which extends from one side of the base or receptacle 7 to the other side thereof. Pivotaly secured at one of its edges to the lower edge of the baffle-plate 13 is another baffle-plate 85 90 14 which also extends from one side to the other of the base or receptacle yet so as to move between said sides. Pivotaly connected at one of its ends to the lower portion of the plate 14 is a rod 15 which has 95 mounted on its upper end a float 16 to rest on the surface of the water 17 contained in said base or receptacle. By this means it is apparent that the deflection of the plate 14 will be regulated by the quantity of water 100 contained in the receptacle or base, for it is obvious as the level of the water is lowered by the evaporation, or raised by supplying water to the tank or receptacle, the float 16 will allow the lower end of the plate 105 14 to be lowered or will cause it to be raised, thus effectually providing, when the water is sufficiently lowered, a baffle for directing

the passage of air from the receptacle or base 7 upwardly through the opening 12 in the cover thereof. Located in the receptacle 7 or base is another float 18 which has 5 extended therefrom through a suitable opening in the cover 8 near the hasp or fastening device 10 an upright rod or member 19 which may be provided with a graduated scale to indicate the quantity of water contained 10 by the base, for it is obvious that the float 18 will rise or fall with the level thereof. The cover 8 is also provided with another opening 20 which is preferably located therein near its hinged end or portion and 15 is for the reception of porous or absorbent material, which in the present instance is shown in the form of a block 21 which is provided with a series of vertically disposed recesses or ways 22 for the passage of air 20 downwardly into the receptacle or base 7 so as to contact in its further passage from the opening 20 in said base to and through the opening 12 thereof with the water. Mounted on the top of the base or receptacle 7 and 25 circumscribing the openings 12 and 20 therein is a heating drum 23 which may be made of any suitable size, form and material, but by preference, of metal and elliptical in shape, in cross-section as shown. This drum 30 may be extended to any suitable height above the top of the base 7 and is provided in its lower portion at a suitable point or place above the top 8 of said base with a horizontally extended floor 24 which together 35 with the top or cover 8 and the walls of the drum 23 form or constitute a humidity chamber 25 which has communication with the receptacle or base 7 through the opening 12 as will be readily understood. 40 stood by reference to Fig. 1 of the drawings. Above the partition or floor 24 of the drum 23 said drum is provided with a series of openings 25^a for the admission of air into said drum, and it will be observed 45 by reference to Fig. 1 of the drawings, that said openings are located below the burner 26 which may be of the ordinary or any well-known construction, and which has communication with and is supported by a 50 tube 27 extended through the wall of the drum 23 and provided at its outer end with a valved device 28 for connecting the tube or pipe to a source of gas supply. As shown in Figs. 1 and 2 of the drawings the burner 55 26 is surrounded by a series of tubes or pipes 29 which are vertically located in the drum and have their ends opening through the partition or floor 24, as well as through the lid or cover 30 for said drum. At its portion 60 adjacent to one end of the base or receptacle 7, the drum 23 is provided with a vertical partition 31 thus forming a conduit 32 between said partition and the adjacent wall of the drum. This conduit 65 communicates at its lower end with the opening

20 in the top or cover 8 of the base and receives the upper portion of the block or absorbent material 21, as is clearly shown in the different views of the drawings. The upper portion of the partition 31 is provided with an opening 33 for the passage of heated air from the drum downwardly through the said conduit and from thence through the ways 22 of the absorbent material and from thence into the water chamber or receptacle 7, and from thence out through the opening 12 in the top of said receptacle into the chamber 25 and from thence through the tubes 29, where the air will be super-heated by the heat from the burner 26, and discharged into the room. The top or cover 30, is by preference, made of sufficient size and shape to close the upper end of the conduit 32 and may be removable from the drum if desired. 85

From the foregoing and by reference to the drawings, it will be readily understood and clearly seen, that when the construction shown in Figs. 1 and 2 of the drawings and above described is employed, gas may 90 be supplied to the burner 26 and there ignited, when by reason of the heat generated by said burner and gas, air will be drawn into the drum 23 through the openings 25, and thus feed oxygen to the flames. 95 In its heated condition and upward passage the air will pass through the opening 33 in the conduit 32 and from thence downwardly in said conduit through the same in the direction indicated by the arrows and also through the passage-ways 22 of the absorbent or porous material 21 and from thence into the base or receptacle 7 above and in contact with the water therein, and from thence out through the opening 12 into the humidity chamber 25 and then up through the tubes 29, from the upper ends of which it will be discharged into the room or apartment. 105

In the above-named construction and 110 operation, it is obvious that as the water in the tank or receptacle 7 evaporates, the floats 16 and 18 will descend with the volume of water, and that in so doing, the indicator rod 19 will point out or indicate about the 115 quantity of water contained in said receptacle, and also that the float 16 will so support the baffle-plate 14 as to guide or direct the air current above the water level in said receptacle, toward the opening 12 in the top thereof. In the above-mentioned 120 operation, air will contact with the upper surface of the water in said vessel, and will also be subjected to the moisture carried by the porous or absorbent member 21 after 125 which it will pass out through the tubes 29 into the room in practically a pure condition and free from deleterious odors, dust or soot, yet carrying humidity about equal to that of the atmosphere. When it is desired 130

to clean out the receptacle or base 7, the hasp 10 may be disengaged from the fastening 11 and the drum tilted so as to raise the cover of said receptacle, to such a position as to admit of access to the receptacle for supplying water or cleaning the same as is apparent.

Having thus fully described my invention, what I claim as new and desire to secure by Letters Patent is—

1. In a stove of the class described, the combination with a water-containing base or receptacle having a pair of openings in its top, of a heating drum vertically mounted on the top of said base about said openings therein and having a vertically disposed air conduit in communication with one of said openings, said drum also having its upper end closed and in its lower portion means for the inlet of air and in its upper portion an outlet for air and the products of combustion, a horizontally disposed partition located within the lower portion of the drum below said air inlet but at a distance above the top of the base, means for holding and burning fuel located in the lower portion of the drum, and a plurality of air tubes located vertically around said fuel holding and burning means and mounted on said partition and the top of the drum but open through the same.

2. In a stove of the class described, the combination with a water-containing base or receptacle having an opening in its top, of a heating drum having its upper end closed, a vertically disposed air conduit connected to the drum and communicating at its lower end with the said base, the said drum also having in its lower portion means for the inlet of air and in its upper portion an outlet for air and the products of combustion, a horizontally disposed partition located within the lower portion of the drum below said air inlet but at a distance above the top of the base, fuel holding and burning means located in the lower portion of the drum, porous or absorbent material located in the base and extended above the water level thereof, and a plurality of air tubes located vertically around said fuel holding and burning means and mounted on said partition and the top of the drum but open through the same.

3. In a stove of the class described, the combination with a water-containing base or receptacle having a pair of openings in its top, of a heating drum vertically mounted on the top of said base about said openings therein and having a vertically disposed air conduit communicating with one of said openings, said drum also having its upper end closed and in its lower portion means for the inlet of air and in its upper portion an outlet for the air and the products of combustion, a horizontally disposed parti-

tion located within the lower portion of the drum below the air intake but at a distance above the top of the base, means for holding and burning fuel located in the lower portion of the drum, absorbent or porous material located in the base and extended into the lower portion of said conduit, and a plurality of air tubes located vertically around said fuel holding and burning means and mounted on said partition and the top of the drum for the intake of air at the lower ends of said tubes and for the discharge of air from their upper ends.

4. In a stove of the class described, the combination with a water-containing base or receptacle having a lid or cover hinged thereto and provided with a pair of openings, of a heating drum vertically mounted on the lid of said base about said openings therein and having a vertically disposed air conduit in communication with one of said openings, said drum also having its upper end closed and in its lower portion means for the inlet of air and in its upper portion an outlet for the air and the products of combustion, a horizontally disposed partition located within the lower portion of the drum below said air intake but at a distance above the lid of the base, means for holding and burning fuel located in the lower portion of the drum, absorbent or porous material located in the base and extended into the lower portion of said conduit and having vertical passage-ways, a plurality of air tubes located vertically around said fuel holding and burning means and mounted on said partition and the top of the drum but open through the same, and a downwardly deflected baffle-plate at one of the edges of one of the openings in the lid of the base.

5. In a stove of the class described, the combination with a water-containing base or receptacle having an opening in its top, of a downwardly deflected baffle-plate at one of the edges of said opening and extended cross-wise of the base, an auxiliary baffle-plate pivotally connected to the lower portion of the first-named baffle-plate and similarly extended, a float loosely connected to the lower portion of the last-named plate, a heating drum having its upper end closed and vertically mounted on the top of said base around said opening, a vertically disposed air conduit connected to the drum and communicating at its lower end with said base, said drum also having in its lower portion means for the inlet of air and in its upper portion an outlet for the air and the products of combustion, a horizontally disposed partition located within the lower portion of the drum below said air inlet but at a distance above the top of the base, fuel holding and burning means located in the lower portion of the drum, porous or absorbent material located in the base and ex-

tended above the water level thereof, and a plurality of air tubes located around said fuel holding and burning means and mounted on said partition and the top of the drum but open through the same.

6. In a stove of the class described, the combination with a water-containing base or receptacle having an opening in its top, of a heating drum vertically mounted on the top of said base around said opening and having a vertically disposed air conduit communicating at its lower end with the base and at its upper portion with the drum, said drum having its upper end closed and provided in its lower portion with means for the inlet of air, a horizontally disposed partition located within the lower portion of the drum below said air inlet but at a distance above the top of the base, a gas burner located in the lower portion of the drum and having communication with a supply of gas, and a plurality of air tubes located vertically around said burner and mounted on said partition and the top of the drum but open through the same.

7. In a stove of the class described, the combination with a water-containing base or

receptacle having an opening in its top, of a horizontally deflected baffle-plate located at one edge of said opening and extended cross-wise of the base, a heating drum having its upper end closed and vertically mounted on the top of said base around said opening, said drum having a vertically disposed air conduit communicating at its lower end with the base and at its upper portion with the drum and provided in its lower portion with means for the inlet of air, a horizontally disposed partition located within the lower portion of the drum below said inlet but at a distance above the top of the base, a gas burner located in the lower portion of the drum and having communication with a supply of gas, a plurality of air tubes located vertically around said burner and mounted on said partition and the top of the drum but open through the same, and absorbent or porous material located in the base and extended into the lower portion of said conduit and having ways for the passage of air. 50
